UNITED STATES PATENT OFFICE.

JOHN A. JOHNSON, OF MADISON, AND TARGE G. MANDT, OF STOUGHTON,
WISCONSIN.

VEHICLE-AXLE.

SPECIFICATION forming part of Letters Patent No. 423,776, dated March 18, 1890.

Application filed November 18, 1889. Serial No. 330,682. (No model.)

To all whom it may concern:

Be it known that we, JOHN A. JOHNSON and TARGE G. MANDT, residents, respectively, of Madison and Stoughton, in the county of Dane and State of Wisconsin, have invented certain new and useful Improvements in Axles for Vehicles; and we do hereby declare that the following is a full, clear, and exact description of the invention, which will enable others skilled in the art to which it appertains to make and use the same, reference being had to the accompanying drawings, which form a part of this specification, and in which—

Figure 1 is a side view of our improved axle with the skeins complete and ready for use, but one of the nuts having been removed. Fig. 2 is a longitudinal sectional view of the same; and Fig. 3 is a sectional detail view, on an enlarged scale, of one end of the axle 20 with the skein or thimble removed.

Like letters of reference denote corresponding parts in all the figures.

This invention relates to metallic axles for vehicles, made round and provided with metallic skeins or thimbles at their outer end; and it has for its object to construct as an improved article of manufacture a metallic axle having skeins which may readily be removed when worn out and which admits of 25 the easy and speedy substitution of new skeins, and that in such a manner that the new skeins will when adjusted always and necessarily assume their proper working position relative to the axle.

With this object in view our improvement consists in the detailed construction and combination of parts of the axle-body proper and the skeins, substantially as will be hereinafter more fully described and claimed.

Reference being had to the accompanying drawings, the letter A denotes the axle proper, which is made round or cylindrical, of steel, iron, or other suitable metal. This axle, as will appear from the drawings, is perfectly straight from end to end; but its extreme outer ends A' are canted and reduced by cutting away both sides on a slant, as indicated at a, said canted and reduced ends being screw-threaded to adapt them to receive the 45 nuts B, so that the inner ends of the nuts will bear up square against the outer ends

of the skeins or thimbles (shown at C) and box B'.

The skeins or thimbles are of the construction shown more clearly in Fig. 2 of the drawings—that is to say, they are cast hollow, with a recess D, and bored through longitudinally, but not centrally—that is to say, the bore E is made to fit the axle closely on a slant or incline corresponding to the pitch 55 and “gather” which the wheel is to have and nearer the under side of the skein than the upper, so that the skeins will be set at the proper angle relative to the body of the axle without the necessity of bending the ends 60 of the latter, so that the axle may be left perfectly straight from one end to the other. This pitch or incline of the skeins C C corresponds to the pitch or slant of the reduced and threaded ends A' A', which receive the 70 nuts B B, so that the latter will always bear up true against the ends of their respective skeins and boxes.

The outer end of the bore E (denoted by the letter E') is threaded, so that the skein 75 may be securely (yet removably) fastened by screwing it upon the threaded ends b b of the axle. As an additional means of fastening, the shoulders or bearings F F, which are integral with and project rearwardly from the 80 skeins, so as to bear against the under side of the axle in the usual manner, are recessed, as shown at f, so as to form a semi-cylindrical chamber surrounding the corresponding portion of the axle on the under side, and 85 after the skein has been adjusted in its proper position upon the axle this chamber or recess f is filled with Babbitt metal or some other composition possessing the same qualities, by means of which (in addition to the threaded 90 end of the axle) the skein is fastened and held securely in its position, or, if preferred, the bearings F F may be left full in the metal and bored out when the skein is bored, so as to exactly fit the axle. At the same time the 95 skein may readily be removed when worn, or if for any other reason it is desired to remove it, simply by knocking out or fusing the filling of Babbitt metal and then unscrewing the skein from its appropriate end of the axle. 100 By this construction and combination of the axle and skeins it will be seen that the former

will last indefinitely, as there is no wear upon it, and no parts are weakened or strained by bending. Any farmer or other person of ordinary intelligence can readily remove the old skeins and substitute new ones, which requires no special tools or appliances other than those which are in every-day use in any farm or blacksmith shop. At the same time the skeins will, by proper adjustment in the boring, always have the proper "set" upon the axle without adjustment or measurement on the part of the person putting on the skeins, which operation, therefore, does not require skilled labor.

Having thus described our invention, we claim and desire to secure by Letters Patent of the United States—

As an improved article of manufacture, a metallic axle for vehicles comprising the following elements in the specified combination, viz: a straight round axle having its extreme outer ends reduced, slanted downwardly by such reduction and threaded to receive the

usual nuts, and the removable hollow skeins bored through slantingly and eccentrically, the outer part of the bore being threaded to adapt it to be screwed upon the threaded outer ends of the straight axle at a pitch or incline corresponding to the pitch of the nutted axle ends, said skeins having recessed rearwardly-projecting shoulders adapted to receive a filling or packing of Babbitt metal or its equivalent as an auxiliary means of fastening, substantially as and for the purpose herein shown and set forth.

In testimony that we claim the foregoing as our own we have hereunto affixed our signatures in presence of two witnesses.

JOHN A. JOHNSON.
TARGE G. MANDT.

Witnesses to signature of John A. Johnson:

A. E. PROUDFIT,
J. H. NICHOLS.

Witnesses to signature of Targe G. Mandt:

BENNETT S. JONES,
